SPOON OR SIMILAR ARTICLE

Johann Brokate, Whitesboro, N.Y., assignor to Utica Cutlery Company, Utica, N.Y., a corporation of New York

Filed Sept. 10, 1965, Ser. No. 86,924

Term of patent 14 years

(Cl. D54—12)

FIG. 1 is a top plan view of a spoon or similar article showing my new design;

FIG. 2 is a bottom plan view thereof;

FIG. 3 is a cross-sectional view on an enlarged scale taken along lines 3—3 of FIG. 1;

FIG. 4 is a side elevational view thereof.

The dominant features of my design reside in the portion of the drawings shown by the solid lines.

I claim:

The ornamental design for a spoon or similar article, substantially as shown and described.
